METHOD OF MAKING A HOLLOW PRO-
PELLER BLADEJohn H. Nelson, Holden, Mass., assignor to Wy-
man-Gordon Company, Worcester, Mass., a
corporation of Massachusetts

Application March 7, 1938, Serial No. 194,330

1 Claim. (CL 28—156.8)

This invention relates to propeller blades for aircraft engines and particularly to hollow blades made of steel or other metal or alloy of high tensile strength and adapted to be forged and welded or brazed. In the following specification and 5 claim, the term "steel" is to be understood to be descriptive only and to include ferrous alloys and all other metals or alloys which meet the requirements above set forth.

10 It is the general object of my invention to provide a hollow steel propeller blade of novel construction, and to provide an improved method of manufacturing such a blade.

More specifically, I provide a hollow steel blade 15 comprising two forged casing portions and a single longitudinal reenforcing rib or stiffening member, all three parts being permanently secured together by welding or brazing operations.

My invention further relates to certain arrangements and combinations of parts and to certain ordered procedure which will be hereinafter described and more particularly pointed out in the appended claim.

A preferred form of the invention is shown in 25 the drawings, in which

Fig. 1 is a plan view of my improved propeller blade;

Fig. 2 is a plan view, partially broken away, and showing forged blanks from which the two 30 casing portions of my improved blade are formed;

Figs. 3 and 4 are transverse sectional views, taken along the lines 3—3 and 4—4 in Fig. 2 respectively;

Figs. 5 and 6 are sectional views corresponding 35 to Figs. 3 and 4 but showing the blanks forged or pressed to finished shape;

Fig. 7 is a perspective view of a portion of the longitudinal stiffening rib;

Figs. 8 and 9 are transverse sectional views of 40 the finished propeller, taken along the lines 8—8 and 9—9 in Fig. 1 respectively; and

Fig. 10 is an enlarged detail sectional view to be described.

Referring to Figs. 1, 8 and 9, I have shown a 45 propeller blade B of hollow cross section and comprising casing portions 20 and 21 and a longitudinal stiffening rib 22, all permanently secured together by welding or brazing in the relative positions shown in Figs. 8 and 9.

The propeller blade B is also provided with the usual hollow circular hub portion 24 by which it is attached to the driving shaft of a suitable engine.

50 The blank 20^a from which the casing portion 20

is formed is shown in cross section in Fig. 3 and comprises two flat and relatively thin side portions 25 and 26 and a relatively heavy upset rib 27 located opposite a depressed portion or groove 28.

It will be understood that the portions 25 and 26 vary in width in different parts of the blank, so as to provide the required stock to form a blade of the varying cross section indicated in Figs. 1, 5 8 and 9.

The blank 21^a shown in Figs. 2 and 4 is similarly 10 provided with flat portions 35 and 36 separated by a relatively heavy upset rib 37 located opposite a depressed portion or groove 38.

After the blanks are formed as described by 15 forging or press operations, the blanks are pressed and folded as indicated by the arrows in Figs. 3 and 4 to the U-shaped sections shown in Figs. 5 and 6. This operation is preferably performed by dies in such manner that the surfaces will be brought to the exact contours required in the 20 finished blade.

The longitudinal strengthening rib 22 is then 25 placed between the edges of the portions 20 and 21 of the blade and the parts are permanently secured together by welding or brazing operations.

In order that all parts may be firmly held from 30 displacement during said welding or brazing operation, the edges of the rib 22 are preferably recessed as indicated at 40 in Fig. 10 to receive the edges of the forged casing portions 20 and 21, 35 which edges have previously been machined to the exact required outlines.

During the pressing and folding operation the hub portions 42 and 43 (Fig. 2) of the blanks may 40 be bent to semicircular form and these parts may 35 be joined together to form the complete hub 24 when the other parts of the blade are welded or brazed.

Having thus described my improved propeller 45 blade and my improved method of making the same, it will be seen that I have produced a hollow steel propeller blade comprising two forged casing portions strongly reenforced at the edges of the blade, and a single additional longitudinal stiffening member to which the forged portions are permanently welded or brazed.

Such a propeller blade has the desired light 50 weight associated with the necessary high tensile strength, and is adapted to resist the severe stresses to which it is subject in operation.

The blade may be twisted to provide the necessary helical pitch at any convenient point in the operations described. Preferably the blade is twisted after the parts are assembled as shown 55 in Figs. 8 and 9 but before the welding operation.

it being desirable that the welding take place after the twisting, as the welded parts will then more firmly retain their helical relation.

The term "welding" as used in the claim is to be understood as including equivalent processes, such as brazing, for permanently securing metal parts together.

Having thus described my invention and the advantages thereof, I do not wish to be limited to the details herein disclosed, otherwise than as set forth in the claim, but what I claim is:

The method of making a hollow metal propeller blade having curved front and rear outer edges and which tapers gradually in width from an intermediate point toward the outer end and abruptly in width from said intermediate point toward the inner end; which method comprises forming a pair of substantially flat forged blanks each having one straight edge and one curved edge and each being widest intermediate its ends and tapering toward the ends; forming in each

blank an integral longitudinal rib of substantially greater thickness than the flat portion of the blank and near the center of the blank which rib is in part longitudinally curved and follows a line approximately midway between the variably spaced edges of said blank throughout the major portion of the length of said blank; bending each blank about its longitudinal rib thereby forming therefrom complementary casing portions of substantially U-shaped cross section and tapering 10 toward each end; assembling said U-shaped casing portions with the rib portions outermost and the inner edges engaging a longitudinal metal stiffening member; and permanently securing the casing sections and said stiffening member by welding 15 the parts together along the lines of juncture, thereby forming a complete propeller blade, wherein the curved offset ribs constitute integral reinforced curved edges for the blade.

20

JOHN H. NELSON.
